REFILL UNIT FOR BALL POINT PENS

Paul R. Kuhn, St. Louis County, Mo., assignor to
Ritepoint Co., St. Louis, Mo., a corporation of
Missouri

Application November 20, 1950, Serial No. 196,594

7 Claims. (Cl. 120—42.4)

1

This invention pertains to ball point pens and particularly to a construction suitable for use in a refill unit for such a pen. This is an improvement on the structure disclosed in the co-pending application of Sylvester G. Lipic, bearing Attorney's Docket No. A-525, Serial No. 189,725, filed October 12, 1950.

In accordance with this invention, generally stated, the refill unit comprises a head in which a suitable tip having a ball point is assembled. An ink container, which may be a flexible bag or a rigid tube, is attached to the said head. A bore extending through the head to the ball point is adapted to convey the ink from said container to said point. Mounted within the ink container is a rod or wire which extends through said bore to the ball point. This rod is loose in the container so that it may move about as the pen is handled. In so doing, the rod moves both laterally and endwise in said bore and thereby serves as an agitator to assist in feeding the ink to said ball.

Two similar embodiments of this invention are illustrated in the accompanying drawing, in which

Fig. 1 is a longitudinal sectional view of a refill unit embodying this invention; and

Fig. 2 is a similar view showing a modified form of the agitator element.

Referring to the drawing, 1 designates a head of metal, plastic, or other rigid material, which may be provided with any suitable type of tip 2 in which a ball point 3 is mounted. A bore 4 extends entirely through the head 1 and the tip 2 down to the ball 3 to provide a passage for ink to be fed to said ball to be transferred thereby to the paper in writing.

An ink container 5 which as stated may be a flexible bag or a rigid tube of metal, plastic, or other suitable material, is secured to the head 1 by any suitable type of fastening 6. If the container 5 is rigid it should be perforated at its upper end to provide for the admission of air thereto as the ink is used up. Mounted within the container 5 is an element 7 in the form of a rod or wire. This element may be rounded at its top end by a curl 8, or the like, so that it may engage the end of a bag without danger of injuring the same. The lower end portion 9 of the element 7 extends through the bore 4 down to a point adjacent the ball 3. In the embodiment of Fig. 1, it is shown as contacting said ball while the upper end thereof has clearance within the end of the container 5 so as to permit a certain endwise movement of the ele-

ment 7. The bore 4 may be large enough to permit also a certain lateral movement of the portion 9 therein.

In the embodiment of Fig. 2 the element 7 is supported against downward movement beyond a certain point by a bend or kink 12 providing a shoulder engageable with the rear end of the head 1. With this arrangement, the element 7 cannot be forced down far enough to dislodge the ball 3.

As the element 7 moves about, within the container 5, such movement being either endwise or lateral, or both, it serves as an agitator to keep the ink in a fluid condition and to assist it to feed along the bore 4. It also tends to break up any bubbles which may have formed in said bore which may interfere with the feed of the ink. Its up and down movement, however, provides a certain pumping action which helps to insure regular feed of the ink. It will be noted also that the rod 9 forms with the bore 4 an annular passage leading from the container 5 to the ball 3. This rod and bore are so proportioned as to make said passage of capillary dimensions in cross section so that capillary action is effective to feed the ink to the ball. In this way said bore may be made of ample size so as to avoid difficulty in manufacturing, and thereafter the passage is reduced to the desired size by insertion of a rod 9 of appropriate diameter.

An outer shield for the container 5 may be provided in the form of a metallic tube 10 secured to the head 1 by any suitable means as by crimping as indicated at 11. Such a shield serves to prevent injury to the container 5, particularly where the latter is in the form of a flexible bag, and also protects the device against any impact tending to force the element 7 downward in the bore 4 sufficiently to dislodge the ball 3 from its socket.

The rod 7 may serve several purposes. It may serve as a support for the container 5, when that is a bag of flexible material and when there is a tendency for the bag to collapse. Thus, it may prevent the bag from collapsing at a mid-section, by reason of which feed would be cut off and the unit put out of service before the ink is exhausted.

It serves also to improve the feed to the ball 3, when the container 5 is flexible or rigid as pointed out above, the rod being movable with a change in position of the pen, it serves to agitate the ink, thereby feeding it by a pumping action to the ball, and also breaks up any air

bubbles which might form to block flow of the ink. Where the bag is of flexible material, the bag does not bear on the rod sufficiently to prevent it from fulfilling its agitating function.

It serves to form a reduced annular capillary passage to the ball, thereby maintaining a supply of ink adjacent the ball, even with the pen upended.

It forms a conductor for the ink. The rod 7, being preferably of metal, such as a steel wire and, therefore, having a high molecular or surface attraction for the ink, and being readily wettable by the ink, assists in quickly supplying the needed ink downward to the ball when the pen is held in writing position. In this position the ink is conducted down the rod to by-pass any obstructing air bubble which may form in the passageway.

The invention is shown as preferably embodied in a refill unit which may be detached from a pen case. It will be obvious, however, that the invention may be embodied in a non-refillable pen in which case the tube or shield 10, or even the container 5, may be so constructed as to be suitable as an exterior pen case.

Various changes may be made in the details of construction, within the scope of the appended claims, without departing from the spirit of this invention. Parts of the invention may be used without the whole and improvements may be added while retaining some or all of the advantages of the invention.

I claim:

1. In a ball point pen, a head having a ball point tip with a ball rotatably mounted in said tip and a bore extending through said head to said ball, an ink container attached to said head adapted to supply ink to said bore, and an agitator loosely mounted in said bore for free movement longitudinally and laterally with respect to said bore and container, and extending from said container to a point adjacent said ball.

2. In a ball point pen, a head having a ball point tip with a ball rotatably mounted in said tip and a bore extending through said head to said ball, an ink container attached to said head adapted to supply ink to said bore, and an agitator loosely mounted in said bore for free movement longitudinally and laterally with respect to said bore and container, and extending from said container to loosely contact said ball.

3. In a ball point pen, a head having a ball point tip with a ball rotatably mounted in said tip and a bore extending through said head to said ball, a flexible ink bag attached to said head, and an extension element loose in said bag abut-

ting the end thereof to keep the same extended and traversing said bore for free movement therein to provide an agitator of the ink therein.

4. In a ball point pen, a head having a ball point tip with a writing ball rotatably mounted in said tip and a bore extending through said head to said ball, a flexible ink bag attached to said head, and an extension element loose in said bag extending to the end thereof to keep the same extended and traversing said bore to provide an agitator of the ink therein and loosely contacting said ball.

5. In a ball point pen, a head having a ball point tip with a ball rotatably mounted in said tip and a bore extending through said head to said ball, a flexible ink bag attached to said head, and an extension element loose in said bag extending to the end thereof to keep the same extended and traversing said bore to provide an agitator of the ink therein, said element being formed with a shoulder engaging said head to limit its movement toward said ball.

6. In a ball point pen, a head having a ball point tip with a ball rotatably mounted in said tip and a bore extending through said head to said ball, a flexible ink bag attached to said head, and a wire strut within said bag having one end rounded for engagement with the end of said bag and the other end positioned to loosely contact said ball.

7. In a ball point pen, a head having a ball point tip with a ball rotatably mounted in said tip and a bore extending through said head to said ball, a flexible ink bag attached to said head, and a wire strut loose within said bag having one end rounded for engagement with the end of said bag and the other end portion traversing said bore to a point adjacent said ball.

PAUL R. KUHN.
